APPARATUS AND METHOD FOR FORMING
AND MOUNTING DAMPER BARS ON GRIDSEdwin F. Nickl, Cedar Grove, N. J., assignor to
Radio Corporation of America, a corporation of
Delaware

Application August 31, 1949, Serial No. 113,347

14 Claims. (Cl. 29—25.17)

1

The present invention relates to an apparatus and method for forming and mounting damper bars from continuous stock in electron discharge devices and more particularly to an apparatus and method for mounting a damper bar on a grid structure having side rods with grid wire thereon.

Damper bars find wide use in electron discharge devices for dampening the vibration of filamentary cathodes to improve operation of the device by reducing microphonics in the output thereof. Some damper bars comprise a straight wire having an insulated portion for engaging the filamentary cathode at a location intermediate its ends for deflecting it laterally, and bare end portions for fixing to supports. Where wound type grids are employed in the device this form of damper bar is usually disposed transversely of the grid side rods and is fixed to one or both of the side rods.

The operation of mounting a damper bar on a wound grid or a grid having side rods with grid wire disposed transversely thereof has heretofore involved a delicate manual operation which has been rendered difficult because of the necessity for accomplishing the fixing of the bar to the side rods without interfering with the grid wire or wires also fixed thereto. Since the manual operation of mounting a damper bar of the type described as heretofore involved critical considerations of appropriate position of the bar longitudinally of the grid, suitable engagement of the grid side rods at a portion thereof intermediate two adjacent grid turns, and effectively welding or otherwise fixing the damper bar to the grid side rods without damage to the grid, this operation has heretofore required a relatively long time for accomplishment and has consequently increased the cost of manufacture while subject to the usual limitations of hand operations. Moreover, prior practices have required the cutting of the damper bar to size and removal of a portion of the insulation therefrom prior to the mounting operation to render it suitable for welding to the grid.

Accordingly it is an object of the invention to provide an apparatus and method for automatically mounting a straight damper bar in an electron discharge device in a more expeditious and accurate manner.

Another object is to automatically and accurately mount a damper bar on a wound type grid from a supply of continuous coated wire.

A further object is to provide an apparatus

and method for improving the adherence of a damper bar to a support.

Another object is to provide an apparatus and method for simultaneously cutting a damper bar from a continuous supply and forming the cut end of the bar for improved adherence to a support.

Another object is to provide an apparatus for automatically positioning a support structure in an appropriately predetermined manner and feeding a damper bar to engage a critical portion of the support structure without damage to other components of the structure.

A further object is to provide an apparatus for automatically positioning a wound grid and a damper bar in appropriate relation so that the damper bar engages portions of the grid side rods intermediate the grid turns thereon.

Another object is to provide an apparatus for feeding a continuous damper bar stock, appropriately positioning a wound grid for receiving a predetermined length of said stock and simultaneously severing surplus stock from the damper bar and bending the severed end of the bar partly around a grid side rod and welding the bent end of the bar around the grid side rod.

A further object is to provide an apparatus for automatically removing the insulation from a stock of insulated wire at predetermined longitudinal portions thereof and fixing predetermined lengths of the stock so treated to a support.

According to the invention, an apparatus is provided including a plurality of means disposed in tandem array to support a grid having side rods, condition damper bar wire stock by removal of part of the insulation therefrom, feed the conditioned wire transversely of the grid side rods and between two turns of the grid, cut and form a desired length of damper bar, and weld the cut and formed damper bar to at least one of the grid side rods. According to the method of the invention a damper bar having bare end portions and an intermediate coated portion is provided by removing a part of the insulation from a continuous supply of insulated

wire, feeding the wire so treated to a grid, subsequently severing the wire to form a damper bar and at the same time forming one end of the bar to improve a weld between said end and one of the grid side rods.

Further objects and features of the invention will manifest themselves as the present description continues.

Referring to the drawing:

Figures 1, 2, 3, 4 and 5 each represent a sec-

tional elevation of the apparatus of the invention, each figure showing the apparatus in a different position.

Thus Figure 1 shows the apparatus in the position of removing a portion of the insulation from damper bar stock and prior to a feeding of the damper bar stock to a grid;

Figure 2 shows the grid rotated so that the side rods are in position for receiving the damper bar stock therebetween;

Figure 3 is a view of the apparatus after the feeding operation;

Figure 4 shows the feeding carriage and insulation removal members moved to engage a fresh length of damper bar stock and the engagement by the welding electrodes of a grid side rod and a portion of the damper bar stock; and

Figure 5 is a view of the cutters moved into position for cutting and bending a portion of the damper bar partly around a grid side rod, the welding electrodes being shown in position for welding the bent portion of the damper bar to the grid side rod.

Referring in more detail to the drawing:

The apparatus shown in Figure 1 is designed to provide straight damper bars from a continuous supply of coated damper bar stock and to mount the damper bars on grids having one or more side rods with transverse wires or turns thereon. Except for positioning the grid on suitable supports of the apparatus and removal of the coating from the initial end of the damper bar stock, the operations of the apparatus are wholly automatic.

The damper bar stock comprises a continuous length of wire 10 having an insulating coating 11 fed from a suitable supply which may be supported on a spool, not shown.

A straight damper bar when ultimately mounted in an electron discharge device includes bare ends, one or both of which may be fixed to spaced supports such as grid side rods. The intermediate portion of the damper bar is provided with an insulating coating for engaging a filamentary cathode to prevent shorts between the cathode and the support structure for the damper bar.

The first operation performed by the apparatus of the invention is to remove the insulation from predetermined longitudinal portions of the coated stock. To this end the apparatus is provided with a pair of hammers, 12, 13 having flat opposing surfaces. As the hammers 12, 13 are caused to approach each other by a power means, not shown, of relatively great force, an impact between said surfaces of the hammers results in a cracking off of the insulation on the portion of the stock between the hammers. This hammering action preferably involves the application of a single blow to the wire which, when accompanied by sufficient force will serve to crack the insulation and cause the same to fall from the wire. A jet of air, not shown, may be employed to complete the removal of the cracked insulating material. At the conclusion of the blow referred to the hammers 12, 13 will extend through the insulation 11 and firmly engage the bar wire 10.

The next operation of the apparatus is to feed the stock having part of its insulating coating removed, as indicated above, to a station where damper bars are cut from the stock and fixed to grids. To this end hammers 12, 13 are caused to move by means, not shown, to the left as 75

viewed in Figure 1 to assume the position shown in Figure 2. This movement of the hammers is in unison with a corresponding movement of a carriage 14. The function of the carriage 14 is to support and guide the end portion of the damper bar stock and to assure delivery of the end portion in a predetermined path and secure desired orientation of an intermediate portion of the stock with respect to the grooves referred to in the hammers 12, 13.

In registry with the path of travel of the damper bar stock and in the order named are spaced cutters 15, 16 and spaced welding electrodes 17, 18. Also supported in registry with said path is a grid comprising grid side rods 20, 21 and grid turns or wires 22, and oriented so as to cause the grid to extend transversely of the path of travel of the damper bar stock and with said path disposed between two adjacent turns or wires of the grid. A mandrel 19 serves to support the grid. This mandrel does not extend into the path of travel of the damper bar stock.

The mandrel 19 is mounted for rotation on an axis longitudinal of the grid. Thus, before the damper bar stock is caused to move to the left beyond the cutters 15, 16 and towards the grid, the mandrel 19 is rotated clockwise by means, not shown, to provide clearance between the grid side rods and the damper bar stock as shown in Figure 2. The mandrel 19 is further provided with means, not shown, for receiving thereon a predetermined longitudinal portion of the grid to permit free entry of the damper bar stock between two adjacent transverse wires or turns of the grid.

After the damper bar stock is extended across the grid side rods 20, 21 with the bare wire portions opposite the grid side rods, the mandrel 19 is caused to rotate counterclockwise to bring the side rods firmly against the bare wire portions of the damper bar stock as viewed in Figure 3. Subsequently the welding electrodes 17, 18 are caused to approach each other by means, not shown, to firmly engage grid side rod 20 and a bare portion of the damper bar stock, to further restrain the portion of the damper bar stock fed to the grid against movement. Under this condition, as shown in Figure 4, the carriage 14 and the spread hammers 12, 13 move to the right to engage a fresh section of damper bar stock.

The movement referred to of the carriage 14 and the hammers 12, 13 is incapable of disturbing the position of the damper bar section engaged by the grid side rods and the welding electrodes. With a portion of the damper bar stock therefore properly oriented and held against the grid side rods with the bare portions of the damper bar engaging the side rods, cutters 15, 16 are brought into action to cut the damper bar stock at a middle portion of the exposed wire adjacent the grid side rod 20 which is closer to the supply of damper bar stock than side rod 21. The upper cutter 15 is formed with a bevelled cutting edge so disposed that a downward movement thereof towards the lower cutter 16, results in a severing of the damper bar stock to provide a damper bar engaging the side rods of the grid and also in a bending of a portion of the cut end of the damper bar partly around grid side rod 20. This bending of the damper bar increases the area of surface contact between the damper bar and side rod 20. This increased surface contact, as shown in Figure 5,

permits more welding current to traverse the parts to be welded, resulting in an improved weld.

It will be noted that the faces of the welding electrodes 17, 18 have oppositely inclined surfaces 23, 24. This inclination is provided to permit the electrodes to engage only one side rod 20 and one end only of the damper bar, leaving side rod 21 and the other end of the damper bar free. By engaging only one side rod and one end of the damper bar, the welding electrodes produce a minimum of strain on the grid on which the damper bar is mounted.

My apparatus is automatic in operation except for the initial removal of the coating from the leading end of a fresh supply of damper bar stock and except for placement of a grid on the mandrel 19.

When a fresh supply of fully coated damper bar stock is used, it is necessary to either manually remove the coating at the leading end portion of the wire to provide an uncoated end portion of a damper bar, or to feed the completely coated wire through the apparatus with a grid emitted therefrom during the first several cycles of operation. The function of the first several cycles in this event would be to remove coating from the leading end portion of the damper bar stock and cut the stock to provide the uncoated end portion having a suitable length required for finished damper bar.

If the first several cycles of the apparatus are utilized to provide a properly uncoated end portion of a damper bar the leading end of the uncoated stock should be manually disposed between the hammers 12, 13 so that the stock extends at least one half of the distance through the hammers. This will provide a desired uncoated portion which is subsequently cut during a following cycle to appropriate length.

Since no grid is carried by the mandrel 19, during the first several stock conditioning cycles referred to, the piece of wire severed during the cutting step readily falls from the electrodes without involving any welding current. The welding electrodes 17, 18 are fixed to movable supports, not shown, that limit the movement of the electrodes towards each other. This movement is limited to the extent that the closest the electrodes can approach each other involves a spacing between them that is slightly less than the spacing represented by the thickness of a grid side rod added to the thickness of an uncoated portion of the damper bar stock. The thickness of the uncoated damper bar portion therefore by itself is insufficient to bridge the spacing between the electrodes when the latter are brought together as closely as the apparatus will permit, with the result that during the stock conditioning cycles no welding action takes place.

It will be noted that several cycles of the apparatus are required for the provision of a suitable uncoated end portion of the initial damper bar produced. This is for the reason that the feed carriage 14 has an appreciable length for support and feed purposes. Thus, at the end of the first cycle the leading end of the damper bar stock will be disposed somewhere along the line represented by the uncoated portion 10a, shown in Figure 5. At the end of the second cycle the leading end will be located along the line of the uncoated portion 10b, also shown in Figure 5. At the end of the third cycle the leading end will be disposed in the path of the cutters 15, 16 and cut to appropriate length. Therefore, the grid should not be mounted on the

mandrel 19 until the beginning of the fourth cycle of operation of the apparatus, which condition is shown in Figure 1. Beginning with the fourth cycle, therefore, the feeding of a properly uncoated damper bar stock to the grid is fully automatic.

It is thus apparent that with the exception of placing the grid on the mandrel 19 and inserting the damper bar stock between the hammers 12, 13 my novel apparatus is fully automatic.

Other readily apparent advantages of my novel apparatus are as follows: The position of the damper bar on the grid is controlled mechanically so that an accurate disposition of the damper bar between the grid turns is assured, thus, eliminating the hazard of damage to the grid. The accurate mechanical control afforded by my apparatus also assures a proper engagement between the uncoated portions of the damper bar and grid side rods, which results in a desired orientation of the coated portion of the damper bar with respect to a filamentary cathode to be damped. A further and overall advantage of my apparatus is a reduction in the time required for mounting a damper bar on a wound grid, thus contributing to a reduction in the cost of manufacture of electron discharge devices in which damper bars are required. The advantages of my novel apparatus are particularly significant in the manufacture of miniature type tubes in which the mounting of a damper bar by manual means is extremely difficult and time consuming.

The elements of my apparatus shown and described herein are to be regarded merely as an illustrative embodiment of my invention. Various modifications may be made in the structure of these elements as will be apparent to persons skilled in the pertinent art without departing from the spirit of the invention and it is consequently desired that such modifications be included within the scope of the invention as pointed out in the appended claims.

I claim:

1. Apparatus for forming and mounting a straight damper bar on a grid from continuous stock of coated damper bar material, comprising impact means for removing the coating from a portion of said damper bar material and for engaging the resultant bare portion for feeding said stock in intermittent steps through a predetermined path, a grid support spaced from said means for supporting said grid transversely of said path for receiving said stock across a predetermined transverse portion of said grid, means for severing said stock between said first named means and said grip support to provide a straight damper bar and means for fixing said damper bar to said grid.

2. Apparatus for mounting a straight damper bar on a grid having two side rods to engage opposite sides of said side rods, comprising means for intermittently feeding straight damper bar stock in a predetermined path, means for supporting a wound grid transversely of said path for receiving said stock between two adjacent turns thereof and with said stock engaging opposite sides of said side rods, means for cutting said stock adjacent one of said side rods to provide a damper bar and for bending said damper bar partly around said one of said side rods, and means for fixing said damper bar to one of said side rods.

3. Apparatus for making a damper bar from continuous coated stock and for mounting the

damper bar on a grid having two side rods, comprising impact means for removing a portion of the coating on said stock and for firmly engaging the resultant bared portion thereof, said impact means being movable in a path longitudinal of said stock when engaging said stock, a grid support for supporting a wound grid for receiving a predetermined length of damper bar stock from said impact means between two adjacent turns of the grid and between said side rods, cutting and forming means between said impact means and said grid support for severing a predetermined length of said stock to provide a damper bar and for bending a portion of said damper bar partly around one of said side rods, and welding electrodes disposed on opposite sides of said one of said side rods for fixing the bent portion of said damper bar to said last mentioned side rod.

4. Apparatus for mounting a damper bar on a grid having grid turns supported on two side rods from a continuous supply of coated damper bar stock comprising impact means for uncoating portions of said stock and feeding the stock in a predetermined path, means for supporting the grid for receiving a portion of said stock between two adjacent turns thereof with one of said uncoated portions engaging one of said side rods, means for supporting one side of said last named side rods, movable cutting means having a beveled edge for cutting said stock adjacent said side rod and approaching from the other side of said side rod for providing a damper bar of predetermined length and for bending a portion of said damper bar partly around said side rod to increase the area of surface contact therebetween, and means for welding said bent portion of said damper bar to said side rod for fixing the damper bar on said grid.

5. Apparatus for mounting a damper bar from continuous coated stock on a grid having grid turns thereon and side rods comprising means for removing the coating from predetermined longitudinal portions of said stock and moving said stock longitudinally, means for supporting and guiding the stock so uncoated to a mounting station, rotatable means at said mounting station for supporting said grid with the space between two adjacent turns in registry with the path of movement of said stock, whereby said grid is rotatable on its longitudinal axis for moving said side rods out of the path of movement of said stock, means adjacent said grid support for cutting said stock to provide a damper bar of predetermined length, said means having a forming surface for bending an end portion of said damper bar partly around one of said grid side rods, and means for fixing said bent portion of said damper bar to said one of said side rods.

6. Apparatus for mounting a damper bar of predetermined length and having bare end portions and an intermediate coated portion on a grid having two side rods and turns of grid wire thereon to engage one side of one of said side rods and the opposite side of the other of said rods, comprising hammers for receiving continuous stock of coated damper bar material and removing said coating from spaced longitudinal portions of said material, said hammers also serving to move said damper bar material longitudinally, additional means for guiding damper bar material fed to it by said hammers in a predetermined path, means for supporting said grid transversely of said path with two adjacent turns on opposite sides of said path, a combined cut-

ter and former between said guiding means and said supporting means for simultaneously cutting a damper bar of predetermined length from said damper bar material and bending an end portion of said damper bar partly around one of said grid side rods, and means for welding said end portion to said one of said side rods.

7. Apparatus for mounting a damper bar on a grid having two side rods and transverse wires supported thereon from a continuous supply of coated damper bar stock, comprising means for removing the coating from longitudinal portions of said stock to provide bare end portions of said damper bar, means for feeding said partly uncoated stock in steps for a distance equal to the length of a damper bar and in a predetermined path, means for supporting said grid transversely of said path with two adjacent transverse wires and the two side rods thereof disposed on different sides of said path, said supporting means being rotatable for causing said side rods to firmly engage opposite sides of said damper bar, means in said path between said feeding means and said supporting means for severing from said stock a predetermined length thereof to provide a damper bar, and means for fixing said damper bar to at least one of said side rods.

8. Apparatus for making a damper bar having a metallic core and an insulating coating thereon with said coating removed at end portions of said bar, and for mounting said damper bar on a grid having side rods and turns thereon between two adjacent turns thereof and fixed to at least one of said side rods, comprising means for removing a portion of said coating on a continuous supply of damper bar stock and feeding said stock in intermittent steps in a predetermined path, means for supporting said grid transversely of said path with the space between two adjacent turns thereof and between said side rods in registry with said path, said last named means being rotatable to cause said side rods to engage opposite sides of said damper bar stock at bared portions thereof, welding electrodes movable to press one of said bared portions against one of said side rods for restraining movement of said damper bar stock, said first-named means being retractable to engage a fresh portion of damper bar stock while said stock is held by said electrodes, and means for severing the portion of said stock engaging said side rods to provide a damper bar, and bending an end thereof partly around one of the grid side rods to increase the area of surface contact therebetween, said welding electrodes being adapted to weld the bent portion of said damper bar to at least one of said grid side rods.

9. Apparatus for making a straight damper bar from coated continuous stock and mounting the same on a wire grid, comprising opposed hammers having opposed surfaces, said hammers being mounted for reciprocating movement, a longitudinal portion of said stock being in registry with said surfaces when said hammers are separated, whereby said hammers remove by impact a predetermined portion of the coating on said stock when they are brought together, said hammers being held together and movable longitudinally of said stock to carry said stock a predetermined distance, means for supporting said grid for receiving transversely thereof and between two adjacent wires thereon a portion of said damper bar stock, means for severing said portion from the remainder of said stock,

and means for fixing said damper bar to said grid.

10. Method of mounting a straight damper bar having bare end portions and an intermediate insulatingly coated portion, on a grid having a side rod and turns on said rod, comprising the steps of hammering a predetermined portion of a continuous stock of damper bar material for removing the insulation thereon, feeding the continuous stock transversely of the grid and between two adjacent turns thereof adjacent said side rod, holding said stock firmly against said side rod, cutting said stock adjacent said side rod to provide a damper bar, and fixing said damper bar to said rod.

11. Apparatus for mounting a straight damper bar from continuous coated stock thereof on a grid having at least one side support rod, comprising combined coating removing and stock gripping means, said means comprising two oppositely disposed and movable members, said members being adapted to receive said stock therebetween and being movable towards each other for engaging a portion of said stock with appreciable impact, whereby the coating on said portion is removed and a resultant bare portion of the stock is engaged by said members, said members being movable while engaging said stock in a direction axially of the stock, means for supporting said grid transversely of said direction, means movable with said members for guiding said stock to said grid and adjacent said at least one side support rod, welding electrodes adapted to hold said support rod against movement and to provide an anvil, a first cutter spaced from said welding electrodes and adapted to provide another anvil, a second and movable cutter mounted in opposed relation to said first cutter and between said first cutter and said welding electrodes, said second cutter having a bevelled end to provide a relatively sharp edge adjacent said first cutter and a relatively blunt edge adjacent said welding electrodes, whereby said second cutter is adapted to first cut said stock to provide a damper bar and then to partly wrap the cut end portion of the damper bar around said support rod.

12. Method of making an electron tube sub-

assembly comprising a grid having a support rod and a straight damper having a coated intermediate portion and an uncoated end portion fixed to said support rod, including the steps of hammering a predetermined portion of said stock to remove the coating therefrom to provide a bare portion, feeding said hammered stock into transverse engagement between said bare portion thereof and said support rod, simultaneously severing said stock and wrapping said bare portion at least partly around said support rod to provide increased contact area therebetween, and welding said severed and wrapped bare portion to said support rod.

15. Apparatus for mounting a straight damper bar on a grid having two side rods to engage opposite sides of said side rods, comprising means for intermittently feeding straight damper bar stock in a predetermined path, means for supporting a wound grid transversely of said path for receiving said stock between two adjacent turns thereof and with said stock engaging opposite sides of said side rods, means for cutting said stock adjacent one of said side rods to provide a damper bar, and means for fixing said damper bar to one of said side rods.

14. Apparatus for mounting a straight damper bar on a grid having two side rods, comprising means for supporting said grid with said side rods thereof lying in a predetermined plane, means for feeding a straight damper having uncoated ends and an intermediate coated portion, in a plane angularly disposed with respect to said first-named plane, means for bending one of said uncoated ends partly around one of said side rods for increasing the contact area therebetween and for urging the other end of said damper bar against the other of said side rods, and means for welding said one of said ends of the damper bar to one of said side rods.
